UNITED STATES PATENT OFFICE.

CHARLES M. BULLER, OF MILWAUKEE, WISCONSIN, ASSIGNOR TO L. J. MUELLER FURNACE COMPANY, OF MILWAUKEE, WISCONSIN, A CORPORATION OF WISCONSIN.

ADJUSTABLE HEAD FOR PIPES.

Application filed May 12, 1921. Serial No. 468,942.

To all whom it may concern:

Be it known that I, CHARLES M. BULLER, a citizen of the United States, and resident of Milwaukee, in the county of Milwaukee, 5 and State of Wisconsin, have invented new and useful Improvements in Adjustable Heads for Pipes, of which the following is a description, reference being had to the accompanying drawings, which are a part 10 of this specification.

This invention relates to improvements in adjustable heads for pipes more particularly adapted for furnace pipes.

In heating buildings with hot air furnaces it is the usual practice to extend round pipes from the furnace in the cellar to the partition walls and connect said pipes to vertical rectangular pipes which extend upwardly through the partitions to the respective rooms to be heated. At the upper ends of the pipes it is usually necessary to mount heads to which registers are connected. While the round pipes are of a standard size, the vertical stacks vary in 25 cross sectional area, due to the different widths of studding and thickness of partitions and in the ordinary construction it is necessary to have different sizes of heads to fit the different sizes of stacks and different sizes of registers.

It is one of the objects of the present invention to overcome this objectionable feature and provide an adjustable head for pipes which may be easily adjusted on the 35 job to fit the various sizes of registers ordinarily used.

A further object of the invention is to provide an adjustable head for pipes of the double wall construction which may be 40 easily adjusted on the job to fit registers of various widths.

A further object of the invention is to provide an adjustable head for pipes which is of simple construction, is strong and durable and is well adapted for the purpose described.

With the above and other objects in view the invention consists of the improved adjustable head for pipes and its parts and 50 combinations as set forth in the claims, and all equivalents thereof.

In the accompanying drawing in which the same reference characters indicate the same parts in all of the views:

55 Fig. 1 is a vertical sectional view of a

portion of the partition of a building showing a vertical stack with one of the improved heads mounted thereon;

Fig. 2 is a front view of the head;

Fig. 3 is a horizontal sectional view thereof taken on line 3—3 of Fig. 2 on a larger scale;

Fig. 4 is a vertical sectional view thereof taken on line 4—4 of Fig. 2; and

Fig. 5 is a perspective view of one of the 65 adjustable members removed from the head.

Referring to the drawing the numeral 8 indicates a building partition, 9 a hot air register, 10 a vertical hot air pipe or stack and 11 the improved adjustable head interposed between the pipe and the register. The head is of rectangular shape and is formed with a lower inlet or stack opening 12 and a side extension outlet or register opening 13. The vertical rear wall 14, and side 70 walls 15, top wall 16 and front wall 17 are of double wall construction and portions of the said walls are stepped as indicated by the numeral 18 in forming the rectangular opening 12 to telescope the upper end of 75 the stack 10 inserted therein. An extension 16' projecting forwardly from the upper part of the double wall 16 forms the top portion of the lateral rectangular extension opening 13 of the head.

A front extension 17' bent outwardly at right angles from a portion of the outer part of the front double wall 17 forms the lower portion of the rectangular extension opening 13 of the head. The forward portions 80 85 90

19 and 20 of the side walls 15 are bent at right angles, in spaced relation, towards each other to form portions of the front wall of the boot. The front edge portions of the inner parts 19 are bent forwardly and then outwardly at right angles as indicated by the numeral 21 and are slightly spaced from the parts 20. Adjustable U-shaped members 22 are positioned between the upper and lower members 16' and 17' 95 100 and are formed with right angularly extending side extensions 23 which slidably extend between the portions 19 and 20. The outer edges of the upper and lower portions of the U-shaped members 22 are bent upwardly and rearwardly to form grooves 24 and 25 into which the front edges of the portions 16' and 17' extend. The inner edge of said upper parts are bent to form grooves 26 which engage corresponding grooves 27 105 110

formed at the front edges of the inner portion of the double wall 16. The upper edge of the inner portion of the double wall 17 is also bent forwardly and downwardly to form a groove 28 which is engaged by grooved inner edge portions 29 of the lower parts of the U-shaped members 22.

As thus constructed the members 22 may be easily moved toward or away from each other to adjust the size of the opening to fit registers of different sizes.

It is also to be understood that the head may also be used in connection with floor registers.

15 From the foregoing description it will be seen that the invention is of very simple construction and is well adapted for the purpose described.

What I claim as my invention is:

- 20 1. An adjustable head for pipes, comprising a rectangular casing having double walls with a side opening and an opening at one end, and an angular U-shaped member slidably adjustably connected to and extending between the double walls of the side portion of the casing provided with the side opening for adjusting the width of the side opening.
- 25 2. An adjustable head for pipes, comprising a rectangular casing having double walls with a side opening and an opening at one end of the casing, and angular U-shaped members slidably adjustably connected to and extending between the double walls of the side portion of the casing provided with the side opening and movable towards and away from each other to adjust the width of the side opening.
- 30 3. An adjustable head for pipes, comprising a double wall rectangular casing having a side opening and an opening at one end,

portions of said casing above and below said side opening projecting laterally outwardly, and angular U-shaped members slidably positioned between said laterally projecting portions and movable towards and away from each other to adjust the width of the side opening.

4. An adjustable head for pipes, comprising a double wall rectangular casing having a side opening and an opening at one end, portions of said casing above and below said side opening projecting laterally outwardly, other portions of the casing adjacent said side opening having grooved edges, and angular U-shaped members positioned between said laterally projecting portions and having grooved edge parts which slidably engage the grooved edges of the casing and being movable towards and away from each other to adjust the width of the side opening.

5. An adjustable head for pipes, comprising a double wall rectangular casing having an outlet side opening and an inlet end opening, outer portions of the double wall of said casing above and below said side opening projecting laterally outwardly, inner edge portions of the double wall of said casing adjacent said side opening having grooved edges, and angular U-shaped members positioned between said laterally projecting portions and having grooved edge parts which slidably engage the grooved edges of the casing and being movable towards and away from each other to adjust the width of the side opening, said U-shaped members also having side extensions which slide between double portions of the double walls.

In testimony whereof I affix my signature.
CHARLES M. BULLER.
